SCAFFOLDING

Howard H. Clark, Kent, Ohio

Application June 21, 1940, Serial No. 341,760

5 Claims. (Cl. 304—2)

My invention relates to an improved scaffolding for use by bricklayers, housepainters and generally in building and in repair and improvement of buildings. It is an object of my invention to provide a simple and inexpensive scaffolding which can be put together or taken down with a minimum of time and expense and which shall reduce the hazards incident to the use of scaffolding, and particularly to do away with the use of nails as the principal means of securing together the several parts of a scaffolding, since nailing damages the parts and since faulty nailing is responsible for many of the accidents occurring in the use of scaffolding.

A specific object is to provide improved extensible uprights or posts of such a character that they can readily be made higher, yet will afford a strong and rigid support for the entire framework.

Another object is to provide an improved joint between sections of the uprights of the scaffolding.

Another object is to provide an improved method of bracing the scaffolding.

Another object is to provide an improved method of supporting putlogs.

Another object is to provide improved means for supporting footboards and material-carrying boards.

Referring to the annexed drawing, which is made a part of this application and in which similar reference characters indicate similar parts:

Fig. 1 is a side elevation of the scaffolding of my invention;

Fig. 2, an end elevation of a typical set-up for veneer work;

Fig. 3, a detail of a joint on an enlarged scale;

Fig. 4, another detail of parts shown in Figs. 1 and 2; and

Fig. 5, a detail of a modification.

In the drawing, reference character 10 indicates a bottom section of an upright in the nature of a pole or post and 11 indicates another section formed for superposition on a section 10. These uprights include any suitable number of sections according to the height desired and each of the sections comprises two parallel bars or side rails 12 and 13 with spacers 14 arranged at suitable distances between them. Screws 13' connect each spacer to the bars 12 and 13 but of course other means may be used to fasten the parts securely together to make a very strong and rigid upright which in fact is found to be stronger

than a solid pole of like material and identical weight.

The bottom sections of the uprights are square at the bottom and throughout their length up to 5 the joint now to be described. At the upper ends of the lowermost sections and at each end of intermediate sections spacers 15 and 16 are provided which are simply duplicates of spacers 14 cut on an angle of about 20° and each attached 10 to a section of the post so as to member or coat with each other in the extension of a post. It will be seen that the respective side bars of an upper section are aligned with and rest directly on those of a lower section, these side bars being 15 of the same cross-section from end to end, so that no part of their strength is lost.

Channel irons 17 and 18 are permanently affixed to the inner side of one section and to the outer side of the coating section by screws 19 20 or the like, the flanges of said channel irons embracing the side bars and providing guides for guiding the spacers 15 and 16 and holding the parts in place, and the channel bars extending beyond the end of the section preferably far enough to embrace the end of the second spacer 25 of the upright, as shown in Fig. 1. For additional security I provide bolts 20, preferably just above and below the membering spacers 15 and 16, said bolts connecting the channel irons and 30 coacting with the spacers to further strengthen the uprights. It will be evident that if the bars 12 and 13 are $1\frac{1}{2}$ " by $3\frac{1}{8}$ ", for example, and the spacers are cut from so-called 2 x 4's with bolts and screws of appropriate size and with strong 35 channel irons, a very strong and rigid structure will result. Actually I propose to use spacers $1\frac{1}{8}$ " thick by 12" long, the spacers 15 and 16 being cut so as to leave three inches of their length in the original rectangular form and the 40 side bars are $1\frac{1}{8}$ " thick or of greater thickness as may be desirable according to conditions.

Each pair of uprights (comprising an inner upright next to a wall and an outer upright farther from the wall) carries a suitable number of 45 putlogs 21 which preferably are so thick as just to fit nicely between the bars 15 and 16 and which rest on the spacers of the respective uprights but are not fastened to the uprights except for small nails, which are used as herein- 50 after explained. Thus they can be pushed inward into position to support footboards 22 or pushed outward so as to be out of the way of the workmen, yet they will still be in position to support material carrying boards 23 or for other uses. Brackets 22' may be secured under the 55

putlogs that carry the footboards, for additional security. These boards and the putlogs, spacers and side bars will usually all be made of stock sizes of lumber, and the channel bars will be made of steel or aluminum. The wooden parts should all be treated so as to prevent absorption of water, and particularly those parts within the joints or splice between upright sections.

The uprights are connected lengthwise of the scaffold by horizontal braces 24 held in place by bolts 25 mounted in the spacers, and by diagonal braces 26, here shown as each carried at one end by a bolt 25 and at the other by a bolt 27 mounted in a spacer located lower down on the other of the pair of uprights, each bolt being long enough to carry the ends of at least three braces, i. e., two horizontal braces extending to right and left therefrom and a diagonal brace. Preferably the braces consist of hollow metallic tubes flattened at their ends with a hole through the flattened part to receive a bolt, but obviously the structure and arrangement of the braces may be varied. Nailed-on ledger boards and cross braces can be added in special cases but it will be seen that generally I avoid all nailing and yet provide a strong and rigid structure that can be put together, taken apart and re-assembled, all in quick time and with no damage to the parts.

The arrangement whereby footboards can be located at any convenient level, and whereby material supporting tables can also be provided approximately waist-high with reference to the footboards, is particularly desirable as conducing to efficiency and reducing fatigue, especially in the case of operations, such as bricklaying, where tremendous waste of time and strength often occurs due to the necessity of incessantly stooping for bricks and for mortar.

The use of braces that can be temporarily secured in place merely by hanging them up at one end is also a matter of great convenience, since it avoids the necessity of many a difficult climb and many an awkward and difficult job of nailing, particularly where one man is working by himself. This outfit can be used anywhere that an upright type of scaffolding can be used.

The provision of readily adjustable putlogs that can be moved forward to support footboards or to bear against a wall for additionally bracing the scaffolding, or moved backward out of the way with their surplus length projecting back of the scaffolding is obviously a matter of great convenience. Usually I secure the putlogs against slipping or lateral movement by means of small nails 30. Also the arrangement of putlogs at convenient intervals (as at 2-foot intervals) is a matter of great convenience, since these putlogs and their uprights serve as a convenient ladder.

It will be obvious that this scaffolding should be set on a level footing and such footing may readily be made of planks and suitable supporting means therefor. When used for veneering or facing, the scaffolding may be secured to a wall or a window ledge by metal straps 31 (Fig. 2).

In Fig. 5 I have shown a modification in which the position of the channel irons 17' and 18' is reversed, the flanges of the two irons extending oppositely away from each other instead of toward each other.

It will be obvious to those skilled in the art that many changes may be made in the device of my invention all without departing from the spirit of the invention, and therefore I do not limit myself to what is shown in the drawing and described in the specification but only as indicated in the appended claims.

Having thus fully described my invention what I claim is:

1. Scaffolding comprising superposable uprights each including a pair of spaced parallel side bars, spacers located at intervals between said bars and secured thereto, and means for maintaining superposed uprights in alignment comprising channel irons respectively adapted to embrace aligned side bars at opposite sides of two superposed uprights, means to secure one of said channel irons to a side bar of one upright and means to secure the other channel iron to the side bar at the opposite side of the other of said sections.
2. A device as in claim 1 including abutting spacing means secured to each upright at the joint between said pair of uprights.
3. A device as in claim 1 including abutting spacing means secured to each upright at the joint between said pair of uprights and bolts passing through said channel irons and said side bars respectively above and below said spacing means.
4. A device as in claim 1, including a spacer on each upright adjacent the joint between them, said spacers having oppositely inclined faces fitting closely against each other when the ends of the side bars are brought into abutting relation.
5. A device as in claim 1, including a spacer on each upright adjacent the joint between them, said spacers having oppositely inclined faces fitting closely against each other when the ends of the side bars are brought into abutting relation the ends of the side bars of each upright terminating respectively at the upper and lower margins of the face of the spacer between said side bars.

HOWARD H. CLARK.
